UNITED STATES PATENT OFFICE.

WILLIAM M. PRYOR, OF ST. LOUIS, MISSOURI, ASSIGNOR TO SOUTHERN MANGANESE STEEL COMPANY, OF ST. LOUIS, MISSOURI, A CORPORATION OF DELAWARE.

SHREDDER-TYPE PULVERIZING HAMMER.

Application filed June 10, 1927. Serial No. 197,800.

The invention pertains to hammers for pulverizing machines, and more particularly to novel hammering or beating elements adapted to be attached particularly to the reels of an ore mill or pulverizing machine.

Difficulty has been encountered in the usual ore machines in providing a hammer of such character that will force the crushed material through the grates so that there will be no tendency of packing the material on the grates if said material is crushed when damp. In many instances, it is desirable that a particular kind of reducing element be provided for a peculiar kind or shape of ore, and it is of course impractical to have reducing elements of different shapes to be substituted for other elements in an ore machine.

It is therefore an object to provide a novel, convenient and inexpensive hammer for ore machines which will effectively perform ore pulverizing functions.

Another object is to provide a hammer having faces adapted to progressively contact the material to be pulverized.

Still another object is to provide a hammer of such character that it may be readily reversed after some faces are worn to present unworn faces to the material acted on by the hammer.

A further object is to provide a tool having cutting ridges separated and disposed in such a manner as to offer additional striking edges to the material to be acted on to thereby increase the working efficiency of the hammer.

Other and more specific objects will readily occur from the detailed description, claims and drawings appended hereto.

In the drawings, wherein like reference characters are used to designate like parts—

Figure 1 is a partial sectional elevation through an ore machine, showing the application of the present invention to the reel thereof;

Figure 2 is a side elevation on an enlarged scale of the improved hammer;

Figure 3 is a sectional end elevation of Figure 2, taken between the attaching arms of the hammer; and

Figure 4 is a bottom plan view of Figure 2.

An ore machine 10 of the usual type is provided with a longitudinal shaft 11 to which the reels 12 are keyed. The ends of

these reels may be bifurcated and have pivoted thereto the improved hammer 13, pivoted by any means such as pins 14 passing through the bifurcated arms of the reels and through a hole 18 provided in the arm 17. The bottom of the machine is provided with a plurality of grate bars 15 having portions so spaced that the crushed or pulverized ore will pass therethrough.

The particular hammer 13, which is the subject-matter of this invention, is formed with a base portion 16 having spaced parallel upstanding arms 17 provided at either end thereof, said arms being provided with aligned holes 18 which, as already described, are adapted to receive the pivot 14. The base is formed having a plurality of stepped ridges, said ridges being shallower adjacent the sides of the base and being graduated to deeper ridges adjacent the center. In other words, ridges 19, 20 and 21 are progressively remote from wall 25 connecting sides of the hammer. These ridges are separated by slots or grooves 22, 23 and 24 respectively, said slots being in overlapping or staggered relation to slots between adjacent ridges. It will be seen that the corners of these slots provided in the striking end offer an additional striking edge which has a tendency to increase the crushing effect of the hammer.

It will readily be appreciated that the old hammer of the slotted type becomes rounded and offers merely a crushing effect, but with this hammer, due to the disposition of the ridges and the slots, a cutting effect is provided as well as a crushing effect, which is very desirable as it has a reducing effect on the material no matter what peculiar shape this material may take. A hammer having a plurality of faces of such character also more readily stirs up the material in the bottom of the machine casing, causing the material to sift through the grates in spite of any moisture therein which may tend to cake or pack the material in the bottom of said casing.

I do not wish to be limited by the exact embodiment shown, which is merely by way of illustration and not limitation, as other and various embodiments will of course be apparent to those skilled in the art.

I claim:

1. An article of manufacture including a series of stepped faces, slots provided in

said articles between said faces, and attaching means for said article.

2. As an article of manufacture, a hammer including a series of stepped faces graduated to dispose the deepest row at the center thereof, and a series of slots provided in said article and disposed between each row.

3. As an article of manufacture, a hammer including a series of rows of stepped faces graduated to dispose the deepest row at the center thereof, and a series of slots provided in said article and disposed between each row, the slots of one row being in overlapping relation to the slots in other rows.

4. As an article of manufacture, a hammer including a series of rows of stepped faces graduated to dispose the deepest row at the center thereof, a series of slots provided in said article and disposed between each row, the slots of one row being disposed in overlapping relation to the slots in other rows, and attaching arms for said article.

5. In a device of the character described, the combination of a base having teeth, said teeth being in stepped relation to each other and separated by slots, and spaced attaching arms formed on said base.

6. In a device of the character described, the combination of a base having ridges thereon, said ridges being separated by slots disposed therebetween.

7. In a device of the character described, the combination of a base having ridges thereon, said ridges being shallower adjacent each side than in the middle, said ridges being graduated from said edge to said middle ridges.

8. In a device of the character described, the combination of a base having ridges thereon, said ridges being shallower adjacent each side than in the middle, said ridges being graduated from said edge to said middle ridges, and slots provided in said device separating said ridges.

9. In a device of the character described, the combination of a base having ridges thereon, said ridges being shallower adjacent each side than in the middle, said ridges being graduated from said edge to said middle ridges, and a plurality of slots disposed in said device between ridges.

10. In a device of the character described, the combination of a base having ridges thereon, said ridges being shallower adjacent each side than in the middle, said ridges being graduated from said edge to said

middle ridges, and a plurality of slots disposed in said device between ridges, said slots being in staggered relation with slots between other pairs of ridges.

11. In a device of the character described, the combination of a base having ridges thereon, said ridges being shallower adjacent each side than in the middle, said ridges being graduated from said edge to said middle ridges, a plurality of slots disposed in said device between ridges, said slots being in overlapping relation with slots between other pairs of ridges, and spaced aligned arms provided on said bar adapted to cooperate with an operating mechanism, said arms being pivoted to said mechanism along an axis parallel to said ridges.

12. A hammer including stepped striking elements, said elements having a greater depth than the distance between the striking faces of said elements.

13. A hammer including stepped striking elements, said elements having a greater depth than the distance between the striking faces of said elements, and means on said hammer for securing said hammer to a reel.

14. A hammer including stepped striking elements, said elements being interconnected at intervals along the striking surfaces thereof.

15. A hammer including stepped striking elements, said elements being interconnected along the striking surfaces thereof, said elements having a greater depth than the distance between said striking surfaces of said elements.

16. A hammer including stepped striking elements, said elements being interconnected along the striking surfaces thereof, said elements having a greater depth than the distance between said striking surfaces of said elements, and means on said hammer for securing said hammer to a reel.

17. A hammer including stepped striking elements, said elements being interconnected at staggered intervals along the striking surfaces thereof.

18. A hammer including stepped striking elements, said elements being interconnected at staggered intervals along the striking surfaces thereof, said elements having a greater depth than the distance between said striking surfaces of said elements.

Signed at St. Louis, Missouri, this 1st day of June, 1927.

WILLIAM M. PRYOR.
